UNITED STATES PATENT OFFICE.

GEORGE M. WHITIN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

HEILMAN COMBER.

1,195,426.

Specification of Letters Patent. Patented Aug. 22, 1916.

Application filed June 18, 1913. Serial No. 774,284.

To all whom it may concern:

Be it known that I, GEORGE M. WHITIN, a citizen of the United States, residing in Whitinsville, in the county of Worcester 5 and State of Massachusetts, have invented the following-described Improvements in Heilman Combers.

The invention is an improvement in the detaching and piecing mechanism and general organization of combers of the Heilman type, adapting such machines for operation with superior efficiency on short staple cotton and permitting rapid operation with extremely close settings and short nip.

To this end the invention consists in the various combinations and relative arrangements of parts hereinafter explained and more particularly pointed out in the appended claims.

In the drawings forming part hereof, Figure 1 is a vertical cross section of one of the heads of a combler incorporating this invention; Fig. 2 a section taken at the ends of the comb cylinder and various rolls; Fig. 3 a top plan of certain parts shown in Fig. 2; Fig. 4 a front elevation of the same; Fig. 5 is a general cross-section of the machine; Fig. 6 a detail of the detaching and pressure rolls on a smaller scale; and Figs. 7 and 8 are details of the holder guides therefor.

Like the ordinary combler of this type, the present machine may be comprised of a number—say six or more—of combing heads all identical in construction, with numerous of the shafts and other operating parts extending through the length of the machine so as to be common to all of the heads. Only one of such combing heads is illustrated herein. The main frame is comprised of a table girder 1 (Fig. 5) mounted on legs and carrying a series of frame uprights 2, which separate the several heads and support the operating mechanism thereof. The sliver apron 3 is mounted on the forward ends of the uprights, this being the table common to all of the heads upon which the combed slivers pass to the draw-box and sliver can, not shown, but which are mounted at one end of the machine. The comb cylinder comprised of a combing or needle half-lap 4 and detaching segment 5, is mounted on the main cylinder shaft 6, which is journaled in the several uprights 2, and driven 55 by the drivehead mechanism at the end of

the machine. This drive mechanism may be of any suitable or usual construction and as it forms no part of the present invention, illustration thereof is omitted. Any combler builder can readily supply the mechanism necessary for imparting to the several parts hereinafter described the motions assigned to them. The comb cylinder is cleared of dirt and noil by means of a rotary brush 7, which doffs to a card-clothed cylinder 8, 65 from which the noil is discharged by an oscillating doffer comb 9.

The roll of lap to be combed is mounted upon the usual lap rolls 10, driven from the end of the machine, and the lap unwinding 70 therefrom passes downwardly and forwardly over the lap plate 11, into the bite of the two feed rolls 12 and 13. The lower feed roll is or may be formed on a shaft co-extensive with the length of the machine 75 and driven by one end intermittently or continuously, as desired. The upper roll is held in place on the lower roll by means of two holder arms 14, and is put under heavy pressure by a superposed presser roll 13^a, 80 the gudgeons of which are likewise held in the arms 14. The said roll engages the upper feed roll principally along the central region thereof, being fluted so as to fit such portion, and its diameter is reduced toward 85 its gudgeons, as clearly indicated in the drawings. Its gudgeons receive the full pressure of the holder arms 14, which are subject to the tension of powerful springs, as shown in Fig. 5, while the feed roll 90 gudgeons, although held in place by the arms, are free of pressure therefrom. The shape of the arms 14 will be understood from an examination of the drawings without explanation. 95

The slenderness of the feed rolls, particularly the upper feed roll, permits it to be set on the lower roll so that its bite thereon will be very near to the line on which the nipper knife nips the cotton without danger of contact with the knife, and further enables common tangent at the line of contact of the said rolls to extend downwardly toward the comb cylinder, toward or adjacent to the bite of the detaching roll upon 100 the segment. The lower feed roll also is set as closely to the rear face of the nipper knife as clearance for the latter will permit, the journal blocks 15 of the lower roll being adjustable on the frame upright 2 for this 105 110

purpose. This method of weighting or pressing slender top rolls forms the subject of another invention and application for patent, Serial No. 773,376, and is preferred 5 when using very slender rolls but any means for weighting the top feed roll without flexing it is suitable, because flexure of the rolls allows the cotton to pull through them under the tension of the detaching operation 10 and results in abnormal waste of cotton. From the feed rolls the lap to be combed is projected into the nipper mechanism which comprises a lower jaw or cushion-plate 16 mounted on a nipper frame 17, 15 which latter is rigidly secured to the frame uprights and in a stationary position with respect to the comb cylinder and the other parts. The means for thus mounting the fixed nipper frame do not appear fully in 20 the drawings but as the same need not differ from constructions ordinarily employed, detailed illustration thereof will not be necessary. Reference may be had if necessary to patent No. 822479 dated June 5th, 1906, for 25 a more complete illustration of this mechanism, as well as other parts of the present machine not constituting this invention and not herein illustrated in detail. It will suffice to point out for present purposes that 30 the cushion-plate 16 is held rigidly on the machine frame with its nipping edge stationed slightly to the rear of the vertical center-line of the comb cylinder and as close as possible to the path of travel of the detaching segment escaping contact therewith. The movable nipper jaw 18 is also of usual 35 construction, being carried by a pair of nipper arms 19, which are fulcrumed at 20 (Fig. 5) and operated through connecting 40 rods 21 from the cam-driven nipper shaft 22, in the lower part of the machine. When the movable jaw or nipper knife opens, the feed rolls advance the lap into the space between the jaws and when the knife descends it nips the projecting fringe thereof 45 against the cushion plate in such manner as to project the fibers toward the cylinder and with a slight rearward inclination whereby they become most effectually 50 combed by the half-lap needles. Directly in front of the nipper knife is mounted the top comb 23, the blade of which is set at an angle, like the nipper knife, as indicated, and as close to the latter as the character 55 of the staple will permit. The teeth of the top comb are set just to escape the comb cylinder, although this setting may be varied by adjustment of a stop-screw 23¹ (Fig. 5). The detaching roll 24 which is leather- 60 covered and supported so as to be engaged by the detaching segment, has no contact whatever with the piecing rolls, later described. It is a slender roll about 14 inches long on its working face and may be three-quarters, five-eighths, or even one-half of

an inch in diameter, according to the length of the cotton. It works on a substantially fixed axis close to the front face of the top comb, which axis is spaced from the axis of the comb cylinder a sufficient distance to enable it to be engaged by the segment, as above stated, but to escape the points of the comb needles, the locus of the latter being about one-thirty-second of an inch lower on the cylinder than the surface of the detaching segment. The forward edge of the segment is sloped or beveled, so that it will ride easily under the detaching roll, exerting the desired pressure thereupon without appreciably shifting its axis. In the present organization it is specially desirable to bevel the segment as just mentioned, because of the slenderness of the detaching roll with which it coöperates although in different organizations, for instance in which the roll is caused to approach the segment, such shaping may not be required. The detaching roll is pressed downwardly so as to provide a firm nip against the segment by means of a presser roll 25, which roll is also independent of the piecing rolls and is subjected to pressure at its ends by means of a pair of stirrups 26, one at each end, the latter being engaged to the weighted levers 27 in an obvious manner. The means for supporting the detaching and presser rolls constitute important features of this invention and are described below, but the invention is not limited to use with presser rolls of any particular kind or to any particular means for imparting the nipping pressure, except as specified in the claims. 100

The tuft held by the nippers during the combing is next engaged by the segment and as the nippers open is pressed against the detaching roll, being at the same time raised into the depending teeth of the opposed top comb 23. The detaching roll partakes of the motion of the segment, coöperating with it to draw the lap forwardly and detach the tuft from the main body of the lap, which is still held by the feed rolls. The tuft parts from the lap in a line substantially coincident with or slightly in rear of the top comb teeth, so that the tail ends of the detached fibers are drawn through the said teeth and cleaned and combed thereby. The slenderness of the detaching roll 24 brings its bite line (upon the segment) close to the top comb teeth and this gives the detaching roll a longer and better purchase upon the tuft, allowing it to grasp more of the shorter fibers than would be the case with a larger detaching roll, which of course—in order to escape the top comb—must be placed farther forward with reference to the top comb and the feed rolls. This close nip with long stapled cotton means a lessening of the waste of shorter fibers, but with short cotton it means that the fibers otherwise too short to 110

be efficiently combed can now be combed without undue loss of material. The disposition of the feed rolls close to the nipper knife and of their common tangent as described, also contributes to the saving of the shorter fiber, for the distance of their bite line to the parting line of the tuft is thereby rendered so short as to cause the short fibers to remain in the lap, rather than to be 10 dragged through the top comb with other fibers caught by the detaching roll.

The piecing rolls which are wholly independent of the detaching roll, as above mentioned, are mounted directly in front of the 15 latter and operate in the present instance to take the detached tuft directly from the segment turning it upward and forwardly. These rolls comprise a rearward piecing roll 28, identified in the claims as the second roll, 20 and a forward piecing roll 29, both mounted in contact with each other, and one or the other being a shaft roll driven from the drive-head end of the machine. In the present case the roll 29 is the shaft roll, *i. e.*, is 25 formed on a shaft extending from the drive-head through all the several combing heads, and its mate 28, is an individual or separate roll for each head, held in contact with the shaft roll and pressed against it by means of 30 a pair of stirrups 30, engaging its gudgeons. These stirrups are hooked to weighted levers 31 beneath the comb cylinder, which levers 31 are adjacent and similar to the weight levers 27 above referred to. In certain 35 forms of this invention the roll 28 may be so placed as to engage the segment, like the detaching roll, in which case it will serve as an auxiliary detaching roll out of contact with the other, but it is preferred that it will escape the segment by an appreciable distance, 40 thus forming a clear passageway between it and the segment through which the tuft passes after detachment, and the lower piecing roll 29 is so journaled that its lower rear side forms a sort of terminal wall to this tuft 45 passageway, opposed to the path of the tuft advancing on the segment. With this arrangement the forward ends of the fibers of each tuft will encounter the side of this roll 50 and be turned upwardly thereby, away from the segment and into the bite of the said roll with the roll 28. To accomplish this result the lower side of the piecing roll 29 should 55 lie below the common tangent of the detaching roll and segment. This tangent is shown by a dotted line in Fig. 1. The two piecing rolls may be one or both fluted, or the roll 28 may be leather-covered. They 60 receive a piecing motion, which, for instance, may revolve them two-thirds of a revolution forwardly and one-third backwardly on each nip of the machine. Thus the tail ends of each tuft will be backed off in a position to 65 be overlapped upon the forward ends of the succeeding tuft, according to the common

mode of operation of the piecing roll shaft of the Heilman type of comber. Upon the steel roll 29 there is placed the ordinary brass clearer roll 32, the same being held in horse-tails 33 of any suitable form, and upon 70 this clearer roll there may also be mounted the usual clearer cover, not shown in Fig. 1, but adapted to be held in the slotted horns of the horse-tails. From the piecing rolls the combed sliver passes to the sliver pan 34 75 (Fig. 5) through its trumpet 35 and the calender rolls 36, onto the apron 3 above referred to, whence it passes through the draw-box to the sliver can.

The piecing roll 28 and the detaching and 80 presser rolls 24 and 25 are supported by their ends upon a common support formed by the pillows 37 which carry the shaft bearings of the piecing roll 29. As shown more clearly in Fig. 2 and the detail figures, these 85 pillows are mounted on the upper, inclined edges of the frame uprights 2, and each has a laterally and rearwardly extending arm 38, which carries adjustable bearings for each of the three rolls referred to. The piec- 90 ing roll 28 is provided with journal sleeves 28¹ on each of its end gudgeons, which sleeves are slabbed on one side to rest upon the flat face of an adjustable bearing block 39, the latter being set on the bracket arm 38 95 in engagement with an adjustment screw 40. By means of this screw it may be set at different elevations to adjust the roll 28 to the appropriate distance from the path of the comb cylinder. The flat top of the block 100 39 inclines toward the piecing roll 29, so that the roll 28 may bear on the latter under the pressure of the stirrup 30, which is applied to its gudgeon sleeve directly over the bearing block.

The detaching roll 24 is provided with a similar gudgeon sleeve 24¹, received in the semi-circular seat 41 of a bearing block 42. This block is mounted on the shelf portion 110 of the bracket arm 38, directly in front of and in contact with the bearing block 39, and like that block is rested upon a set screw, by which the position of the detaching roll with reference to the axis of the comb cylinder may be properly adjusted. A 115 tightening bolt 43^a passing through registering slots in both bearing blocks and threaded into the forward side of the bracket arm 38, serves to clamp both bearing blocks in their independently adjusted positions. 120 The block 42 has two upwardly extending horns 43 adapted to receive the bearing 44 for the gudgeon sleeve 25¹ of the presser roll. The latter sleeve is slabbed on its op- 125 posite vertical sides and is capable of rectilinear motion in the oblong slot in its block 44 and its position in the said block is determined by means of a thrust screw 45 tapped into the upper portion of the block, as indicated in the drawings. When 130

the presser roller is placed in the sleeves and the latter are mounted in the blocks 44, the said blocks are placed between the horns 43 of the detaching roll bearing and moved 5 downwardly therein until the presser roll engages the detaching roll. The stirrup 26 is then placed upon the top of the block 44, exerting its pressure through the stop screws 45 and gudgeon sleeves upon the presser 10 roll to press the same upon the slender detaching roll, and the latter upon the segment. By the arrangement and inclination of the horns or guiding means the effort of the stirrups is exerted to press the detaching roll downwardly but toward the rear side of the comb cylinder, which direction is important inasmuch as otherwise the occurrence of bunches is likely to break the framework or other parts.

15 20 The presser roll may, with some adjustments of the machine, be simply a cylindrical body of plain steel unfluted, extending substantially the length of the detaching roll upon which it rests, but inasmuch as it 25 must be subjected to heavy pressure and is therefore liable to flexure, its bearing upon the detaching roll is relieved near the ends, leaving a bearing portion 25^a (Fig. 6) of full diameter at the central region. By thus 30 localizing the pressure at or along a central portion of the detaching roll, it is possible to give it uniform pressure upon the segment, even when it is of much smaller diameter than indicated in the drawings. The full 35 diameter of the presser roll may thus extend for four or five inches at the center of a 14 inch roll, or it may be longer and should be longer when the detaching roll is reduced to less than one-half inch diameter. 40 As the weight of the presser roll itself is not relied upon to produce the pressure, it may be as slender as the constricted space in which it works demands. It may run under slight constant flexure without imparting unequal distribution of the pressure 45 to the detaching roll. It is possible to make both the detaching and presser rolls hollow so that their mass will be as low as possible thereby permitting them quickly to 50 take up the motion imparted by the segment.

It will be observed that the weighting stirrups 26 and 30 are placed side by side, the one bearing on the presser roll and the other on the second roll or rearward piecing 55 roll, both being disposed in the space between the horse-tail base 33^a and the pillow 37, in which position they will be confined out of contact with other parts. Each stirrup has a finger-hole at its top but their 60 shapes are such that the apertured portion of each projects above or beyond the corresponding apertured part of the other and thus enables either one to be readily lifted or removed when desired.

65 From the foregoing description it will be

understood by those skilled in the art that the principles of the present comb are not confined to the particular structure shown but that various modifications and changes in the size, proportions and relative arrangement of the parts, may be resorted to, and that new parts may be added or certain parts removed from the structure illustrated without sacrificing the benefits of the invention above pointed out.

70 75 I claim:

1. In a Heilman type comb, the combination with the feed and nipper mechanism, a top comb and a comb cylinder having a detaching segment thereon, of a segment-80 engaging detaching roll, fixed bearings holding the latter close in front of the top comb, and a pair of piecing rolls in front of said detaching roll coöperating directly with the segment to remove the tufts therefrom and adapted to piece the same together.

2. In a Heilman type comb, the combination with the feed and nipper mechanism, a top comb in front of the latter and a rotary comb cylinder opposed to the top 90 comb having combing and detaching segments thereon, of a small segment-engaging detaching roll, end bearings therefor supporting said roll in front of the top comb, a presser roll superposed upon said small 95 roll and preventing flexure thereof, and a pair of piecing rolls in front of said detaching and presser rolls deflecting and receiving the detached tufts directly from the segment and adapted to form a continuous 100 lap thereof.

3. In a Heilman type comb, the combination of a rotary comb cylinder having a detaching segment, means that are stationary with respect to such cylinder for holding 105 a fringe of lap in engagement therewith, a detaching roll mounted in front of the said means to nip the fringe against the segment, and a pair of piecing rolls mounted in front of the said detaching roll 110 operating independently of said detaching roll to deflect and receive the detached tufts from the segment and piece the same together.

4. In a Heilman type comb, the combination of a top comb, a rotary comb cylinder having a detaching segment, stationary means for holding the fringe of lap in engagement with the cylinder, a small-diameter 115 segment-engaging detaching roll mounted in front of the top comb and adapted to detach and draw the cylinder-combed tuft through the top comb, means for imparting nipping pressure to said small roll without flexing the same, and a pair of piecing rolls in 120 front of the said detaching roll, correlated with the segment to deflect and remove detached tufts from the segment and adapted to piece the same together.

5. In a Heilman type comb, the combi- 130

- nation of feeding and nipping means for a cotton lap, a rotary comb cylinder having a segment, a segment-engaging detaching roll adapted to detach the tuft, an independent roll out of contact with said detaching roll adapted to turn the end of the tuft away from the segment, and means coöperating with said latter roll to piece the tufts together. 5
- 10 6. In a Heilman type comber, a top comb maintained in fixed position, stationary means for advancing and nipping the uncombed lap, and a rotary comb cylinder having a detaching segment, in combination with a small-diameter detaching roll mounted in front of said fixed top comb and adapted to engage the segment to draw the tuft through the top comb, a presser roll applied to said detaching roll and a 15 pair of piecing rolls in front of said detaching and presser rolls, one of said piecing rolls being correlated with the segment to turn the head of the tuft outwardly away from the segment. 20
- 25 7. In a Heilman type comber, a rotary comb cylinder having a detaching segment and means for advancing and nipping the lap, in combination with a segment-engaging detaching roll mounted in front of the 30 nipping means, a second roll revolving on a fixed axis in front of the detaching roll and removed from the path of the segment, a third roll engaging the second roll, the said second and third rolls being intermittently operated to deflect the tufts from the segment and piece the same together. 35
8. In a Heilman type comber, a comb cylinder having a detaching segment, a detaching roll engaged thereby, a second roll 40 in front of said detaching roll and spaced from the path of the segment, a third roll in contact with the second roll with its lower side disposed below the common tangent of the detaching roll and segment 45 whereby such roll turns the forward end of the tuft upwardly and into the bite of said roll and the second roll, said second and third rolls being intermittently rotated to piece the detached tufts. 50
- 50 9. In a Heilman type comber, a comb cylinder having a detaching segment, a slender detaching roll adapted to engage the segment, a second roll in front of this detaching roll but out of contact with it and 55 with the segment, a third roll in contact with the second roll and mounted so that its side toward the axis of the comb cylinder extends inwardly of the common tangent of said detaching roll and segment, means for 60 operating the second and third rolls to piece the detached tufts together, and suitable means for weighting the said detaching roll without flexure. 65
10. In a Heilman type comber the combination of means for feeding the lap and nipping the fringe thereof, a comb cylinder, a detaching roll, a presser roll for the latter, gudgeon guides for the said presser roll and means for weighting the ends or gudgeons thereof. 70
11. In a Heilman type comber, means for feeding the lap and holding the fringe, a cylinder for combing the fringe having a detaching segment, a small-diameter segment-engaging detaching roll adapted to 75 nip the fringe, a presser roll held in superposition upon the said detaching roll, weighting stirrups applied to the ends of the presser roll, and independent means for piecing the detached tufts. 80
12. In a Heilman type comber, a comb cylinder having a detaching segment, means for feeding the lap and holding the fringe in engagement with the cylinder, a segment-engaging detaching roll of small diameter 85 adapted for close nip on the fringe, means applied to the central region of such roll for imparting pressure thereto, and means out of contact with said detaching roll for removing the tuft from the segment. 90
13. In a Heilman type comber, a comb cylinder having a detaching segment, means for feeding the lap and nipping the fringe, a small detaching roll adapted to nip the fringe against the segment, an end-weighted 95 superposed roll having an enlarged diameter in its middle portion engaging the middle portion of the small roll, and separate means for removing the detached tufts. 100
14. In a Heilman type comber, a comb cylinder having a detaching segment, nipper jaws, and a pair of feed rollers set close in rear of the nipper jaws, a top comb, and a small-diameter detaching roll set close to the top comb and adapted to engage the segment whereby the bite of the said roll upon the segment is close to the bite of the feed rolls, in combination with a pair of intermittently operated piecing rolls removed from the said detaching roll and coördinated with 105 the segment to deflect and remove detached tufts therefrom and piece the same together. 110
15. In a Heilman type comber, a comb cylinder and detaching roll, a pair of nipper jaws, a forwardly inclined top comb in 115 front of the nipper jaws, a lower feed roll in rear of such jaws, an upper feed roll of smaller diameter held on the forward side of the lower roll so that their common tangent extends toward the combing cylinder, 120 and means independent of the detaching roll for piecing the detached tufts. 125
16. In a Heilman type comber, a comb cylinder, a detaching roll, a presser roll superposed thereon and a pair of piecing rolls, in combination with a stirrup engaging the end of the presser roll and urging the detaching roll in a rearward direction and an adjacent stirrup engaging one of the piecing rolls. 130

17. In a Heilman type comber, the combination of a detaching roll, a separate pair of piecing rolls and means for supporting the ends of such rolls comprising an arm, a bearing for each roll carried on such arm and means for independently adjusting one of such bearings. 5
18. In a Heilman type comber, a comb cylinder, a detaching roll, a separate pair of piecing rolls, separate bearing blocks for the detaching roll and for one of the piecing rolls, and means for changing the elevation of either block with reference to the comb cylinder. 10
19. In a Heilman type comber, a small diameter detaching roll independent of the piecing mechanism, a superposed presser roll thereon, bearing sleeves for the gudgeons of the latter roll and means for imparting pressure to said sleeves to press the roll upon the detaching roll. 15
20. In a Heilman type comber, a detaching roll, a superposed presser roll bearing blocks receiving the gudgeons of the latter roll, means for adjusting the position of the gudgeons with respect to the blocks and means for imparting pressure to the blocks. 25
21. In a Heilman type comber, a detaching roll of small diameter, a combing cylinder having a detaching segment with which it engages, a presser roll superposed on the detaching roll, stirrups applied to the ends of the presser roll and guiding means for both rolls whereby the detaching roll is pressed toward the rear side of the combing cylinder. 30
22. In a Heilman comber, a detaching roll and a pair of piecing rolls, one of the latter and said detaching roll being subject to pressure, in combination with an arm carrying a bearing block for each of said rolls and a single tightening member adapted for securing both blocks in their relative positions. 40
23. In a Heilman type cotton comber, a rotary comb cylinder having a detaching segment, means for advancing the lap comprising a lower feed roll, an upper feed roll of smaller diameter held on the forward side of the lower feed roll, and means for nipping the lap during the operation of the rotary comb, in combination with a top comb and a segment-engaging detaching roll in front of the nipping means, a second roll in front of the detaching roll and a third roll engaging the second roll and coöperating therewith to deflect the detached tufts from the segment and to piece the tufts together. 50
24. In a Heilman type comber, a rotary comb cylinder having a detaching segment, means for advancing the lap comprising a lower feed roll and an upper feed roll held on the forward side of said lower roll and means for nipping the lap during the action of the rotary comb, in combination with a 55
- top comb in front of the nipping means, a detaching roll in front of the comb, and a pair of intermittently driven piecing rolls mounted to rotate on fixed axes in front of the detaching roll and in positions wherein they will deflect and remove detached tufts from the segment and piece the same together. 70
25. A Heilman type comber having a combing cylinder with a detaching segment, feeding and nipping means for a cotton lap, a segment-engaging detaching roll, supporting means for the latter which permit the same to yield forwardly and upwardly on impact with the segment, weighting means therefor which urge the said roll toward the rear of the combing cylinder and means out of contact with said detaching roll for piecing together the tufts detached by it. 75
26. A Heilman type cotton comber having a comb cylinder with a detaching segment thereon, means for subjecting a cotton lap to the action of such cylinder comprising a lap-holding means adapted to hold the forward end of the lap in contact with the cylinder needles at a point in rear of the vertical center thereof, a top comb in front of such means, a segment-engaging detaching roll operating in front of such top comb, means for supporting such roll whereby it may yield forwardly and upwardly on impact with the segment, weighting means for said roll which urge it toward the rear of said cylinder, and means out of contact with said roll for piecing the tufts detached by it. 80
27. A Heilman type cotton comber having a combing cylinder with a detaching segment thereon, means for supplying cotton lap thereto, comprising a nipper mechanism including a forwardly inclined jaw mounted to nip the fringe of lap at a point in rear of the vertical center of the combing cylinder, a pair of feed rolls close in rear of said jaw, the common tangent of said feed rolls being inclined downwardly, a top comb inclined correspondingly to said nipper jaw, a detaching roll mounted in front of said inclined top comb, supporting means for said roll adapting it to yield forwardly and upwardly on impact with the segment, pressure means urging said roll rearwardly and downwardly and means separated from the detaching roll for piecing the tufts detached by it. 85
28. A cotton comber of the kind described having a combing cylinder with a detaching segment, stationary means for feeding cotton lap thereto and holding the same to the action of said cylinder and at a point in rear of the vertical center thereof, a segment-engaging detaching roll in front of the said holding means adapted for close nip on the combed fringe and a pair of rolls 90

forward of said detaching roll coöperating with the segment to deflect the detached tufts therefrom and piece the same together.

29. A cotton comber of the kind described comprising a comb cylinder having a detaching segment, a pair of nipper jaws, the lower jaw being stationary and the active jaw being inclined forwardly, a pair of feed rolls close in rear of said jaws, the upper roll being of small diameter, means for holding the same on the forward side of the lower feed roll and close to the path of said active nipper jaw, in combination with an inclined top comb mounted on arms whereby it may be manually turned upward from its operating position, a segment-engaging detaching roll close in front of said top comb and independent means forwardly spaced from the said detaching roll for piecing the tufts detached thereby.

30. In a cotton comber of the kind described, the combination of a comb cylinder having a segment, a pair of nipper jaws, a pair of feed rolls adapted to be set close in rear of said jaws and comprising upper and lower rolls, both provided with sharp intermeshing flutes, a top comb, a segment-engaging detaching roll operating in front of said top comb with close nip on the lap held by said fluted feed rolls, and independent forwardly spaced means for piecing the tufts detached by said detaching roll.

31. In a Heilman type cotton comber, the combination of a comb cylinder having its segment radially higher thereon than the needle half-lap, means for feeding a cotton lap thereto, nipper means whereby such lap is held during the action of the cylinder needles thereon, a segment-engaging detaching roll, means out of contact with said detaching roll for piecing the tufts detached by it, and fixed bearings for said detaching roll and said piecing means adapted to hold the former clear of the needle half-lap and the latter in a fixed relation to the said comb cylinder.

32. In a cotton comber of the kind described, having a comb cylinder with a segment, a top comb, an independent detaching roll mounted close in front of the top comb and a second roll in front of said detaching roll but out of contact therewith, in combination with a frame upright between adjacent heads of said comber, a bracket member on said upright provided with a rearwardly extending arm, a bearing for said detaching roll supported on the extreme rearward end of such arm, and provided with means for

adjusting said detaching roll toward and from the cylinder, and a second bearing 60 formed on the same arm forward of the detaching roll bearing thereon and adapted to support the said second roll.

33. In a cotton comber of the kind described having a comb cylinder, detaching roll and independent piecing means, the combination with the frame upright between adjacent combing heads, of a pillow block on said upright provided with a rearwardly extended arm, a shaft roll journaled on said pillow 70 block and constituting the driving member for said piecing mechanism, and two roll bearings supported at the rear end of said arm, the rearmost bearing being adjustable and adapted to support the said detaching 75 roll and the forward bearing forming one of the supports for the piecing mechanism.

34. In a Heilman type comber, the combination with the lap feeding and nipping means, the comb cylinder and the detaching 80 and piecing rolls, of weighting stirrups for the piecing rolls and separate stirrups for imparting pressure to the detaching roll, the former having upstanding grip portions offset with respect to grip portions of the latter, whereby either stirrups may be grasped 85 for disengaging them without obstruction by the other.

35. A cotton comber of the kind described comprising a comb cylinder with a detaching segment, feeding and nipping means for a cotton lap adapted to hold the forward end of the same in engagement with the cylinder at a point in rear of its vertical center, a segment-engaging detaching roll, supporting 90 bearings for the latter comprising slots 95 inclined toward the rear of the comb cylinder, and means forwardly spaced from said detaching roll for piecing the tufts detached thereby.

36. In a cotton comber of the kind described, the combination of the lap feeding and nipping means, top comb, comb cylinder and piecing means, with a segment-engaging detaching roll interposed between the top 105 comb and the piecing means, a presser roll imparting nipping pressure to the detaching roll and means for weighting said presser roll.

In testimony whereof, I have signed this 110 specification in the presence of two witnesses.

GEORGE M. WHITIN.
